UNITED STATES PATENT OFFICE.

FRANCIS S. DANGERFIELD, OF AUBURN, NEW YORK.

MATCH-SAFE.

SPECIFICATION forming part of Letters Patent No. 229,101, dated June 22, 1880.

Application filed December 30, 1879.

To all whom it may concern:

Be it known that I, FRANCIS S. DANGERFIELD, of Auburn, in the county of Cayuga and State of New York, have invented certain new and useful Improvements in Match-Boxes; and I hereby declare that the following is a full, clear, and exact description of the same, reference being had to the accompanying drawings, making a part of this specification, in ⁵ which—

Figure 1 represents a perspective view of the match box or safe as closed. Fig. 2 represents a perspective view of the same as open and its cover provided with screws to secure ¹⁵ the box to a wall or other stationary object. Fig. 3 represents a vertical section of the match-box closed. Fig. 4 represents a rear view, in perspective, of the box-cover. Fig. 5 represents a stopper-plate or shield removed ²⁰ from the box-cover. Fig. 6 represents detached views of the match striker or igniter and its clamp or holder. Fig. 7 represents a detached view of the spring-arm and holder used to advance the matches. Fig. 8 represents ²⁵ detached views of the above holder and its spring. Fig. 9 represents detached views of the match-elevating foot and bottom guide.

My invention relates to that class of match-boxes designed more especially for carrying in ³⁰ the pocket, although having also the requisite construction to be readily attached to walls, furniture, &c., and is an improvement upon the match-box for which I obtained Letters Patent No. 217,345, dated July 8, 1879, by ³⁵ which improvement I am enabled to obtain a lighter box, capable of being secured to stationary objects or carried in the pocket, and made with some of its parts stronger and more durable.

My invention consists in a match box or safe made so thin or narrow as to accommodate only ⁴⁰ one row of matches at a time. It is closed on one side with a cover, grooved or perforated at the back and permanently pivoted to the body of the box, and said cover retains a spring-arm peculiarly indented and curved, to ⁴⁵ advance the matches. The box also contains a match striker or igniter provided with fan-shaped grooves secured in a clamp having a curved bottom, and a conical or beveled foot

secured to a slide having strengthening corrugations and projections to facilitate its function.

The invention will first be described in connection with the drawings, and then pointed ⁵⁵ out in the claims.

In the drawings, A represents the match-box. It is made of thin sheet metal, as tin, brass, nickel, &c., cut of suitable form, as shown, and slotted in the middle at a. The ⁶⁰ top and bottom edges are turned up, and the sheet is bent in the middle adjoining the slot a, bringing the turned edges in contact and in position to be soldered and form a box too narrow to hold more than one row of matches ⁶⁵ at a time. To the bottom of this box is soldered, in the interior, a guide-plate, b, (shown detached in Fig. 9), inclined toward the front of the box to facilitate the advance of the matches. This plate is furthermore depressed at b' to ⁷⁰ form a cavity for the reception of the match-elevating foot c, and so that the bottom edge of said foot will not form a ridge in front of the advancing matches. This foot c is made of sheet metal bent in the form of a half-cone, with a ⁷⁵ projecting bottom large enough to conveniently receive the lower end of a match, m, but with a tapering or conical upper end too small to engage with the lower end of a short match, and made to direct it upon the projecting bottom. About half-way of the length of this foot the metal is cut and bent to form a projecting arm, c', long enough to pass through the slot a of the box, and through a slot, d, in the slide D, to which it is riveted. ⁸⁰ This slide is made of thin sheet metal bent to embrace loosely the edge of the box; and to prevent it, after some use, becoming bent or jammed against the sides of the match-box, this slide is corrugated across the back, as at ⁸⁵ d', to stiffen, strengthen, and prevent it from bending under pressure. It is also formed with projections embossed thereon, to prevent it slipping between the fingers of persons using it.

Within the upper part of the box is placed the striker or igniter, formed of a strip of spring-steel, e, securely clamped at one end in a piece of sheet metal, f, bent around it at f' by suitable mechanism, leaving the other end free to ⁹⁵ ¹⁰⁰

be elevated by a match in its passage out of the box A, the top of which is turned up adjacent to the opening a' for the free play of the striker. The bottom of the clamp f is bent 5 or inclined upward at the front end to direct the matches toward the opening a' , kept in the top of the box for their exit. The striker-clamp is provided with lugs f^2 , by which it is afterward soldered to the box through the opening a' , and with a turned-up end, f^3 , for the same purpose. The front end of the striker is provided on the under side with peculiar fan-shaped serrations, which I have ascertained, after experimenting with various forms, to be 10 the best for the purpose, as they more than combine the longitudinal and transverse grooves heretofore in use, but start the radial abrasions on the match-tip from one focus, from which ignition is thus induced with more 15 certainty.

The match-cover G is also made of sheet metal suitably bent, and with round corners, where the metal is soldered from the inside, producing a strong joint and a smooth finish 20 on the outside. Within this cover is soldered a bent plate, h . One of its functions is to form a stop for the edge of the box to abut against and prevent it from entering too far within 25 the cover. I have provided the rear edge of the cover with a groove, g , against the sharp or slightly serrated edges of which a match held in the hand can be struck and lighted, and this kind of striker will retain its efficiency 30 for years, the bent plate h forming, then, also a shield to prevent ignited material entering 35 the box. The rear of said shield may also be serrated.

I make these match-boxes of three sizes. As the largest size is also suitable as a stationary 40 match-safe, I provide simple means for securing it to walls, brackets, furniture, &c., these means being two screws, s , passing from within the cover through holes g' in its rear edge. In constructing boxes for the pocket 45 these holes are generally omitted.

To advance the matches toward the front of the box I have provided a substantial spring-arm, I, having its free end so bent as to press against the matches about the middle of their length, 50 whether the box is full or nearly empty. To secure this arm loosely but strongly to the cover of the box, I use a piece of thin metal, (as tin,) k , bent first in the form shown in Fig. 8, to the lower end of which is riveted a trans- 55 verse pin, k' . The upper end, k^2 , is then partly bent within and one end of the bent spring l clamped or secured thereby. The arm I having been previously formed (at one operation) with a small notch or indentation, i , in the upper 60 under side and a larger indent, i' , in the upper

side, the arm I is pressed on the spring l and along it until the transverse pin k' enters the notch i and constitutes its pivot. The lower end of the arm abuts against the lower end of the piece k , and the lower end of the spring l 65 finds its seat in the larger indent i' . When the pieces forming this attachment have been assembled the piece k is soldered within the cover, as shown in Fig. 3, in such a position as to be out of the way while filling the box 70 with matches, as shown in Fig. 2. The lower end of the cover being cut away at g^2 , a stop is thus formed to retain the box at right angle to its cover while fully open. The cover is permanently secured to the box by a pin, a^2 , extending through the sides of both, and this pin is covered and protected by the inclined plate or guide b . The upper edge, A', of the box is chamfered down to produce a close fitting of the cover on the box without strain- 80 in the parts.

Having now fully described my invention, I claim—

1. The combination of the box A, guide-plate b , depressed at b' , and match-elevating 85 foot c , made conical or tapering at its upper end, substantially as and for the purpose de- scribed.

2. The combination of the box A, slotted at a , a match-elevating foot having an arm pro- 90 jecting through said slot, and a slide, D, hav- ing corrugations, substantially as and for the purpose described.

3. The combination of the box A, sheet-metal clamp f , provided with lugs f^2 and f^3 , and a 95 spring-striker, e , provided with fan-shaped ser- rations, substantially as and for the purpose de- scribed.

4. The combination of the box A, cover G, groove g in the edge thereof, and internal 100 shield and cover-stop h , substantially as and for the purpose described.

5. The combination of the box A, cover G, cut away at g^2 , and pivoted to box, perfora- 105 tions g' , and screws s , passing through the edge of the cover, substantially as and for the purpose described.

6. The combination of a match-box cover, spring l , clamp k , provided with a transverse pin, k' , and bent arm I, having indentations i and i' , substantially as and for the purpose de- scribed.

7. The combination of the box A, cover G, cover-stop h , clamp k , having bent extremity k^2 , pivot-pin k' , spring l , and bent arm I, sub- 115 stantially as and for the purpose described.

FRANCIS S. DANGERFIELD.
